UNITED STATES PATENT OFFICE.

WILLIAM H. SAUVAGE, OF NEW YORK, N. Y., ASSIGNOR, BY MESNE ASSIGNMENTS,
TO THE GOULD COUPLER COMPANY, A CORPORATION OF MARYLAND.

SLACK ADJUSTER.

Application filed May 17, 1924. Serial No. 714,168.

To all whom it may concern:

Be it known that I, WILLIAM H. SAUVAGE, citizen of the United States, residing at New York, in the county of New York and State 5 of New York, have invented certain new and useful Improvements in Slack Adjusters, of which the following is a specification.

This invention relates to improvements in slack adjusters and more particularly to that 10 type of automatic slack adjusters illustrated and described in my prior Patent No. 1,227,947, dated January 12, 1915.

One of the objects of the present invention is to provide an improved slack adjuster of 15 the above general character which will be reliable and efficient in use and operation and particularly adaptable to that type of rigging known as clasp brake rigging for the trucks of railway cars.

20 A further object is to provide an automatic slack adjuster of the above general type having relatively few parts which may be inexpensively manufactured and assembled and applied to the brake rigging for 25 now in use without material modification.

Other objects will be in part obvious from the annexed drawings and in part indicated in connection therewith by the following analysis of the invention.

30 This invention accordingly consists in the features of construction, combination of parts and in the unique relation of the members and in the relative proportioning and disposition thereof, all as more completely outlined herein.

To enable others skilled in the art so fully to comprehend the underlying features thereof that they may embody the same by 40 the numerous modifications in structure and relation contemplated by this invention,

drawings depicting a preferred form have been annexed as part of this disclosure, and in such drawings like characters of reference denote corresponding parts throughout all 45 the views, in which—

Figure 1 is a side elevational view of such parts of the complete mechanism applied to one wheel as is necessary to fully understand the application thereof;

50 Figure 2 is a plan view thereof partly in section; and

Figures 3 and 4 are detail sectional views.

Referring now to the drawings in detail, 55 indicates one wheel of an ordinary railway truck on the opposite sides of which are

mounted live and dead levers 6 and 7 respectively. These levers carry intermediate their ends brake shoe heads 8 each provided with a shoe adapted to co-act with the periphery of the wheel 5. The lower ends of 60 the levers 6 and 7 are connected respectively at the points 10 and 11 with a tie rod 12 of the duplex type, as shown more clearly in Figure 2, that is, the rod is in two parts connected at their ends through housings or 65 members 14 and 15, each provided with an opening 16 in which the lower end of the levers are mounted. One member 15 is provided at one side with a temporary take-up 70 and holding housing 17 containing a dog 18 normally held in canted position by means of a spring 20 within the housing 17. This dog or temporary take-up and holding means is preferably a flat piece of metal 75 provided with an opening through which an adjusting rod 21 is adapted to pass. The opposite end of the rod 21 is provided with a lost motion slot 22 surrounding the pivot pin 23 enclosed in a bushing and supporting the 80 brake shoe head 8, as shown in Figures 3 and 4. It will also be noted by reference to Figure 2 that the housing or member 15 is provided with a push rod 24 which passes through a second housing 25 also provided with holding dogs 26 held in canted position 85 by means of a spiral spring 27 surrounding this rod. Interposed between the housing 17 and an adjustable stop 28 on the adjusting rod 21 is a spiral spring 29 which is adapted to be compressed on excess movement of the brake rigging due to wear of the parts, and expand on release of the 90 brakes to restore the parts to normal position and permanently take-up and hold the 95 excess travel.

In order that the above may be more clearly understood, a brief statement of the operation is as follows: On application of the brakes the upper end of the live lever moves relatively towards the right, as indicated 100 by the arrow adjacent pull rod 30, and reacts through the connecting rod 12 at the lower end to also move the dead lever towards the wheel 5 and bring the brake shoes into engagement with the periphery. 105 If excess travel occurs exceeding that provided for by the slot 22 then the adjusting rod 21 is moved towards the right and the exact amount of excess travel is retained 110 by means of the temporary dog 18. The

spring 29 interposed between the relatively moving housing 17 and stop 28 is also compressed a corresponding amount.

When the brakes are released the live and dead levers return to normal position under action of restoring spring 31 and balance spring 32, and the rod 21 causes the member 15 to be moved relatively towards the left a corresponding amount and in this movement the take-up rod 24 is moved relative to the dogs 26 in housing 25, which permanently takes up and holds the excess travel. It will be understood by reference to Figures 1 and 2 that the duplex rods 12 are freely movable relatively to the member 15, sliding in recesses in the sides thereof, as clearly indicated.

It will thus be seen that the present invention contemplates a simple and practical automatic slack adjuster particularly applicable to clasp brake rigging for railway trucks, and is well adapted to accomplish among others all of the objects and advantages herein set forth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of the invention and, therefore, such adaptations are and should be intended to be comprehended within the meaning and range of equivalency of the following claims.

I claim:

1. In an automatic slack adjuster of the clasp brake type, in combination, live and dead levers, the upper ends of which move relatively towards each other during the application of the brakes, a tie rod connecting the lower ends of said levers, and fulcrums intermediate the ends of said levers carrying brake shoes adapted to be brought into engagement with the periphery of the wheel, said tie rod being relatively movable with respect to its point of connection with the dead lever, a temporary take-up mechanism associated with said point of connection, an adjusting rod connecting said point with the live lever near the pivot point of the live lever, a take-up rod, and permanent take-up and holding means associated with the lower end of the dead lever and said rod.

2. In an automatic slack adjuster of the clasp brake type, in combination, a live

lever, a dead lever, a tie rod connecting the lower ends of said levers, an adjusting rod extending from said live lever to a point adjacent the lower end of said dead lever adapted to be actuated on excess travel of the brake rigging, temporary take-up and holding means associated with said adjusting rod, a take-up rod pivotally connected with the lower end of the dead lever, permanent take-up and holding means co-acting with said rod, and a spring near the lower end of the dead lever adapted to be compressed on excess travel of the brake rigging and to expand or move said permanent take-up rod relative to its holding means.

3. In an automatic slack adjuster of the clasp brake type, in combination, a live lever, a dead lever, a tie rod connecting the lower ends of said lever adapted to be placed under tension on application of the brakes, temporary take-up mechanism associated with the lower end of the dead lever, an adjusting rod having a lost motion connection at one end and extending between said temporary take-up mechanism and the live lever adapted to be actuated on excess travel, permanent take-up and holding means including an adjusting rod at the lower end of said dead lever, and means adapted to be actuated on excess travel on release of the brakes to actuate the permanent take-up and holding means.

4. In an automatic slack adjuster of the clasp brake type, in combination, a live lever, a dead lever, a tie rod connecting the lower ends of said lever adapted to be placed under tension on application of the brakes, a housing associated with the lower end of the dead lever having a temporary holding dog, an adjusting rod co-acting with said holding dog at one end and having a lost motion connection with the live lever at the opposite end, a take-up rod pivotally connected with the lower end of said dead lever, permanent take-up and holding means including a plurality of dogs co-acting with said holding rod, and means at the lower end of the dead lever adapted to be actuated on application of the brakes and then on release of the brakes to move the lower end of the dead lever relative to the tie rod, whereby the excess travel of the brake rigging is permanently taken up and held on the take-up rod.

In witness whereof I have signed my name.

WILLIAM H. SAUVAGE.
